[57] CLAIM

The ornamental design for a can watch, as shown and described.

DESCRIPTION

FIG. 1 is a top plan view of a can watch showing my new design;

FIG. 2 is a right side elevational view thereof, the left side being a mirror image thereof;

FIG. 3 is a rear elevational view thereof;

FIG. 4 is a front elevational view thereof;

FIG. 5 is a top plan view thereof in an open position; and,

FIG. 6 is a right side elevational view thereof in an open position.

The broken line showings of a band in FIGS. 1-2 and 5-6 are environmental only and form no part of the claimed design.

FIG. 1

FIG. 2

FIG. 3

FIG. 4

FIG. 5

FIG. 6
